UNITED STATES PATENT OFFICE.

FRANK HENNEBÖHLE, OF CHICAGO, ILLINOIS.

BALANCED HYDRAULIC VALVE.

SPECIFICATION forming part of Letters Patent No. 763,889, dated June 28, 1904.

Application filed October 30, 1903. Serial No. 179,143. (No model.)

To all whom it may concern:

Be it known that I, FRANK HENNEBÖHLE, a citizen of the United States, residing at Chicago, in the county of Cook and State of Illinois, have invented certain new and useful Improvements in Balanced Hydraulic Valves, of which the following is a specification.

One of the objects of this invention is the production of a simple and compact valve for controlling the inlet and outlet to a double-acting hydraulic cylinder, automatically opening the outlet of one end of such cylinder with the opening of the inlet to the other end of the cylinder.

15 A further object of the invention consists in the various improvements in valves of this character hereinafter shown and described.

In the accompanying drawings, Figure 1 is a view showing my improved valve in side elevation. Fig. 2 is a vertical central section through said valve, taken on the plane of the dotted line 2 2 of Fig. 3. Fig. 3 is a horizontal section through the valve-casing, taken on the plane of dotted line 3 3 of Fig. 2. Fig. 25 4 is a similar view on dotted line 4 4 of Fig. 2. Fig. 5 is a fragmental vertical section on dotted line 5 5 of Fig. 3. Figs. 6, 7, and 8 illustrate my said invention as applied to a three-way valve to be used in connection with 30 single-acting hydraulic cylinders, Fig. 6 being a side elevation of said improved valve; Fig. 7, a vertical section on the plane of dotted line 7 7 of Fig. 8, and Fig. 8, a horizontal section through the valve-casing on the 35 plane of dotted line 8 8 of Fig. 7.

In the embodiment of this invention and referring particularly to that form illustrated in Figs. 1, 2, and 3, I provide a casing A, having valve-chambers a' , a^2 , a^3 , and a^4 therein 40 and beneath said chambers and alined therewith the discharge-chambers a^5 , a^6 , a^7 , and a^8 , which valve-chambers and discharge-chambers are connected in pairs by openings a^9 , the upper ends of the walls of which openings 45 are outwardly inclined to form valve-seats. The valve-chambers a' and a^3 are connected by a port a^{10} , and the discharge-chambers a^5 and a^8 are likewise connected by a port a^{11} , said ports a^{10} and a^{11} extending substantially 50 at right angles to each other. At one side of

the casing I provide an inlet-opening a^{12} , placed in communication with the valve-chamber a' by means of the port a^{13} , and at the opposite side of the casing form an outlet-opening a^{14} , which by means of the port a^{15} communicates with the discharge-chamber a^8 . In the remaining sides of the casing A, I form openings a^{16} and a^{17} , the former of which is connected by the port a^{18} with the valve-chamber a^4 and by means of the port a^{19} with the discharge-chamber a^7 , while the latter opening (a^{17}) is placed in communication with the valve-chamber a^2 by means of the port a^{20} and with the discharge-chamber a^5 by means of the port a^{21} . The walls at the outer ends of 65 the valve-chambers a' , a^2 , a^3 , and a^4 of the discharge-chambers a^5 , a^6 , a^7 , and a^8 , the inlet-opening a^{12} , the outlet-opening a^{14} , and the two openings a^{16} and a^{17} are each internally screw-threaded for a purpose to appear hereinafter.

The valve-stems B', B², B³, and B⁴ are adapted to lie within the valve-chambers a' , a^2 , a^3 , and a^4 , respectively, and are provided with taper closures B⁵, intended to be seated in the 75 tapering openings a^9 . The closures B⁵ are fixed in any suitable manner with relation to their stems, and beneath said closures said stems are formed with the radial guide-wings B⁶. Above the closures each of the valve-stems is provided with a piston B⁷, held in place upon said stem between an integral collar B⁸ and a locking-sleeve B⁹, which sleeve has a screw-thread connection with the valve-stem. In order to render the valve substantially balanced, the closures B⁵ and pistons B⁷ are made of substantially the same 80 diameter. Each of the valve-stems is also provided with an axial opening B¹⁰, closed at its lower end by means of a screw B¹¹ and 90 tapped intermediate the ends of the stems by means of the openings B¹² and B¹³. The upper end of each of the valve-stems B', B², B³, and B⁴ is provided with a yoke B¹⁴, secured thereto in any suitable manner, as by means 95 of a screw-thread connection, and with the jam-nut B¹⁵ to permit of an adjustment of the position of said yoke with reference to the closure B⁵. An operating-lever B¹⁶, bifurcated at its lower end to provide two T-shape 100

arms B^{17} and B^{18} , surmounts the valve-stems B' , B^2 , B^3 , and B^4 , the transverse extremities of said T-shape arms B^{17} and B^{18} being pivotally connected with the yokes B^{14} by means 5 of screws or pins B^{19} .

The upper ends of the valve-chambers a' , a^2 , a^3 , and a^4 are closed by means of the bushings C , each of which bushings is provided with a screw-threaded stem C' , adapted to fit 10 closely within the internally-screw-threaded neck of said valve-chambers. In each of the bushings C is formed a cylinder C^2 , alined with the valve-opening a^9 , through each of which cylinders one of the valve-stems passes 15 and in which cylinder one of the pistons B^7 closely fits. At its upper end the bushing C is closed by means of a stuffing-box C^3 of ordinary construction, having a packing-ring C^4 of leather or other suitable material, se- 20 cured therein.

The lower open ends of the discharge-chambers a^5 , a^6 , a^7 , and a^8 are likewise closed with bushings D , having screw-threaded stems D' to correspond with the similar screw-threads 25 within the necks of said discharge-chambers, and the lower extremities of the bushings D are provided with stuffing-boxes D^2 , having packing-rings D^3 for closely surrounding the valve-stems.

30 It will be noticed that the cylinders C^2 communicate, respectively, with the discharge-chambers a^5 , a^6 , a^7 , and a^8 by means of the openings B^{12} and B^{13} and the axial opening B^{10} in the valve-stems. By this means the 35 pressure above the closure B^5 of each of the valve-stems is equalized with that below said closure, and the valves thus balanced. In order to provide for a seating of the valve, it is desirable that the pressure above the 40 closure be slightly greater than the pressure tending to raise it from its seat. Therefore it will be noticed that each of the valve-stems within the cylinders C^2 is of a diameter slightly less than at a point below said closure. 45

In operation a valve of the kind hereinbefore described is connected through the inlet-opening a^{12} with the compressing means by a pipe, (not shown,) and with the opposite ends 50 of a hydraulic cylinder by pipes communicating with the casing at the openings a^{16} and a^{17} . The outlet-opening a^{14} is provided with a discharge-pipe. (Not shown.) Assuming that the pressure-cylinder, the valve, and the pipes 55 mentioned are filled with water under pressure, the pressure-water entering the inlet-pipe a^{12} passes through the port a^{13} to the valve-chamber a' and from this chamber through the port a^{10} to the valve-chamber a^3 , 60 in which chambers a' and a^3 pressure-water stands. Moving the operating-lever B^{16} in the direction of the arrow, as indicated in Figs. 1 and 2, raises the closures B^5 of the valve-stems B^2 and B^3 from their seats, permitting pressure-water to flow to the hydrau- 65

lic cylinder through the port a^{19} and the opening a^{16} . This movement of the operating-lever also permits discharge-water to flow from the opposite end of said hydraulic cylinder through the opening a^{17} in the valve-casing, 70 through the port a^{20} into the valve-chamber a^2 , and to discharge therefrom into the discharge-chamber a^6 , thence through the port a^{15} and the outlet a^{14} . A movement of the operating-lever in the opposite direction raises 75 the valve-stems B' and B^4 , lifting the closures B^5 from their openings a^9 and permitting pressure-water to flow from the valve-chamber a' through the opening a^9 , through the discharge-chamber a^5 , the port a^{21} , and the opening a^{17} to that end of the hydraulic cylinder that was recently discharged. The movement of the operating-lever last mentioned also opened the discharge from the opposite end of said hydraulic cylinder through the 85 opening a^{16} , the port a^{18} into the valve-chamber a^4 , through the opening a^9 into the discharge-chamber a^8 , through the port a^{11} into the discharge-chamber a^5 , and through the port a^{15} to the outlet-opening a^{14} . 90

In Figs. 6, 7, and 8 a hydraulic valve is shown by means of which pressure-water may be supplied to and removed from a single-acting hydraulic cylinder. In this modified form a casing E is provided with valve-chambers E' and E^2 and with discharge-chambers E^3 and E^4 , connected in pairs, respectively, by means of the openings E^6 , the walls of which openings are inclined to form valve-seats. On one side of the casing are two 100 openings E^6 and E^7 , the first an inlet-opening, the latter an outlet-opening, and on the opposite side is an opening E^8 , through which the valve is placed in communication with a hydraulic cylinder. (Not shown.) Valve-stems F' and F^2 are provided for the valve-chambers E' and E^2 , respectively, each of which valve-stems has a closure F^5 and guide-vanes F^4 . Each also has an axial opening F^3 , closed at its lower end by a screw F^6 and 105 tapped intermediate the ends of said valve-stems by means of the openings F^7 and F^8 . The upper end of each of the stems carries a yoke F^9 , adjustably held upon the stem by means of a screw-thread connection and the 110 jam-nut F^{10} . The transverse arms F^{11} of a T-shape operating-lever F^{12} lie within the yokes F^9 and are pivotally connected therewith by means of the screws F^{13} . The remaining parts of this modified form of valve are the same 115 as in the principal form. In the operation of said modified form pressure-water enters the valve-chamber E' through the inlet-opening E^6 . A movement of the lever F^{12} in the direction of the arrow, Fig. 7, permits the pressure-water to pass from the chamber E' , through the opening E^5 , through the discharge-chamber E^3 , and thence through the opening E^8 to the hydraulic cylinder. (Not shown.) By 120 moving the operating-lever F^{12} in a contrary 125 direction the pressure-water is prevented from passing through the valve-chamber E^2 and the discharge-chamber E^4 to the outlet-opening E^8 . By moving the operating-lever F^{12} in a contrary 130

direction the closure F^3 of the valve-stem F^2 is lifted from its seat and water is permitted to escape from said hydraulic cylinder through the opening E^8 , the discharge-chamber E^4 , and 5 the outlet E^7 .

It is clear that various changes may be made in this valve without departing from the spirit and scope of my invention, wherefore I desire to have it understood that I do 10 not limit myself to the particular construction herein shown and described.

I claim as my invention—

1. In a hydraulic valve, in combination, a valve-casing having valve-chambers and discharge-chambers therein, and a valve-seat in 15 each of said valve-chambers; a cylinder alined with each of said valve-chambers; an inlet and an outlet closure for said valve-seats; and a valve-stem for each of said closures carrying 20 a piston within its cylinder, each of said stems having means for placing one of said discharge-chambers and one of said cylinders in communication with each other.

2. In a hydraulic valve, in combination, a 25 valve-casing having four valve-chambers and four discharge-chambers therein, and a valve-seat in each of said valve-chambers; a cylinder alined with each of said valve-chambers; two inlet and two outlet closures for said 30 valve-seats; a valve-stem for each of said closures carrying a piston within its cylinder, each of said stems having means for placing one of said discharge-chambers and one of said cylinders in communication with each other; 35 and means for longitudinally sliding each of the inlet valve-stems and the corresponding one of the outlet valve-stems synchronously.

3. In a hydraulic valve, in combination, a valve-casing having valve-chambers and discharge-chambers in pairs therein; a cylinder alined with each pair of chambers; a valve-closure in each of said valve-chambers; a stem for each of said closures, each stem lying within one of the valve-chambers, one of the 45 discharge-chambers and one of the cylinders; and a piston on each valve-stem within its cylinder, said stem being provided with an opening communicating between its discharge-chamber and its cylinder.

4. In a hydraulic valve, in combination, a 50 valve-casing having four valve-chambers and

four discharge-chambers therein, and a valve-seat in each of said valve-chambers; a cylinder alined with each of said valve-chambers; two inlet and two outlet closures for said 55 valve-seats; a valve-stem for each of said closures, each of said stems having means for placing one of said discharge-chambers and one of said cylinders in communication with each other; a piston on each valve-stem within its cylinder; and an operating-lever bifurcated at one end to provide two T-shape arms, each of said arms being connected with an inlet valve-stem and an outlet valve-stem.

5. In a hydraulic valve, in combination, a 60 valve-casing having four valve-chambers and four discharge-chambers in pairs therein; a cylinder for each of said pairs of chambers and alined therewith; two inlet valve-closures and two outlet valve-closures for said valve-chambers; a stem for each closure, lying within one of the valve-chambers, one of the discharge-chambers and one of the cylinders and being provided with an axial opening 65 communicating between its cylinder and its discharge-chamber; a piston on each valve-stem within its cylinder; and means for positively sliding in either direction each of the inlet valve-stems and the corresponding one of the outlet valve-stems synchronously. 70

6. In a hydraulic valve, in combination, a valve-casing having four valve-chambers and four discharge-chambers in pairs therein; a bushing for each of said pairs of chambers, having a cylinder alined with said chambers; 75 a valve-closure in each of said valve-chambers; a stem for each of said closures, each stem lying within one of the valve-chambers, one of the discharge-chambers and one of the cylinders; and a piston on each valve-stem 80 within its cylinder, of substantially the same diameter as said closure, each stem being provided with an opening communicating between its discharge-chamber and its cylinder to the rear of said piston, said stem being of 85 a larger diameter between said closure and piston than in other portions of its length. 90
